UNITED STATES PATENT OFFICE.

FRANCIS H. RICHARDS, OF HARTFORD, CONNECTICUT, ASSIGNOR TO THE KEMPSHALL MANUFACTURING COMPANY, OF ARLINGTON, NEW JERSEY, A CORPORATION OF NEW JERSEY.

PLAYING-BALL.

SPECIFICATION forming part of Letters Patent No. 727,201, dated May 5, 1903.

Application filed October 6, 1902. Serial No. 126,019. (No model.)

To all whom it may concern:

Be it known that I, FRANCIS H. RICHARDS, a citizen of the United States, residing at Hartford, in the county of Hartford and State of Connecticut, have invented certain new and useful Improvements in Playing - Balls, of which the following is a specification,

This invention, relating to playing-balls, and especially to those adapted for the purpose of golf, has for its object to improve the shell or cover of the ball, thereby giving to the entire structure the requisite qualities of "putting," "approach," and "long drive."

One form of the invention is illustrated in the drawings, forming a part of this specification, in which—

Figure 1 illustrates the ball, partly broken away, disclosing its construction; and Fig. 2 shows a segment of the shell construction.

Throughout the figures similar characters of reference indicate like parts.

The main feature of this invention is embodied in the shell A, which, in the present instance, comprises an outer casing 1 on the inner casing 2, preferably formed of celluloid. Intervening said casings 1 and 2 is a layer 3, formed by granulating cork, mixing it with a celluloid solution, collodion, or a derivative of pyroxylin *a* in a fluent condition. This material after hardening is stiff, hard, and springy and has other qualities whereby it is well adapted to form a filling between said casings for the purpose of securing a materially-increased stability without entirely overcoming flexibility. Moreover, this filling can be made at such a low cost as to effect a material reduction in the expense of making a ball.

The celluloid of the casings 1 and 2 becomes incorporated or united with the celluloid or pyroxylin *a* in the layer 3, thus minimizing the liability of separation of the casings from said layer and the layer in practice forms an excellent backing for the celluloid, minimizing the liability of the latter to crack and rendering the ball highly efficient in "driving" and "putting."

In forming the layer the compressible core

and celluloid mixture is preferably hardened under pressure and heat, the pressure being maintained while the hardening of the layer substance takes place, so that the cork and collodion or pyroxylin with which it is mixed are permanently compressed. Hence an increased resilience is stored up in said layer, which aids in the prompt recovery of the shell A when distorted by a blow, thereby increasing the liveliness of the ball. The resistance of the cork in the layer to further pressure is, however, so great as not to be unduly affected by a light blow, and hence the ball is found to be excellent for putting.

It will be further understood that the pyroxylin in the layer is in the form of a continuous irregular honeycomb or agglomeration of cells and is hence quite stiff and resisting, especially since it is backed by the particles of compressed cork, and conduces to the playing qualities of the ball.

In using the term "cork" or "granulated cork" I mean to include all substances therefor—such, for instance, as sawdust.

The shell A in the present instance surrounds a plastic filling B—such as soft rubber, preferably molded rubber—and this sphere in the present instance incloses a small center piece C of any suitable material. It is understood, however, that various forms of fillings may be employed within the scope of this invention and that modifications may be resorted to with respect to the shell.

It will be seen that the ball comprises two separating casings or shells 1 2 of plastic material, the space between which is occupied by a composition, one of whose components is of similar plastic material and unites with said shells, thereby forming a substantial three-layer shell or cover, which is both highly efficient and also well adapted to withstand the punishment received in a game of golf, especially when celluloid or a derivative of pyroxylin is employed for the outer shell. It will also be noted that this composition shell comprises a structure of phenomenal resilience and stability, which effects an immediate recovery from distortion due to impact.

Variations of structure and materials may be resorted to within the scope of this invention.

Having described my invention, I claim—

- 5 1. A playing-ball comprising a springy core, a shell thereon of hard plastic material, an outer shell of similar material, and a layer uniting said shells and consisting of similar material incorporated with granulated 10 springy substance.
- 15 2. A playing-ball comprising a springy core, a shell thereon of hard plastic material, an outer shell of similar material, and a layer uniting said shells and consisting of similar 15 material incorporated with granulated cork.
- 20 3. A playing-ball comprising a springy core, a shell thereon of hard plastic material, an outer shell of similar material, and a layer uniting said shells and consisting of similar 20 material incorporated with springy granulated substance which is held under compression.
- 25 4. A playing-ball comprising a springy core, a shell thereon of hard plastic material, an outer shell of similar material, and a layer uniting said shells and consisting of similar 25 material incorporated with granulated cork held under compression.
- 30 5. A playing-ball comprising a springy core, a shell thereon of hard plastic material, an outer shell of similar material, and a layer uniting said shells and consisting of granulated 30 springy material incorporated with pyroxylin and held under compression, the pyroxylin uniting with the material of said shells.
- 35 6. A playing-ball comprising a plurality of shells of plastic material and an intervening layer uniting said shells and consisting of 35 similar plastic material incorporated with springy granulated material, the latter being held under compression.
- 40 7. A playing-ball comprising a plurality of shells of plastic material and an intervening 40 layer uniting said shells and consisting of similar plastic material incorporated with granulated cork, the latter being held under compression.
- 45 8. A playing-ball comprising a plurality of shells of celluloid and an intervening layer 45 uniting said shells and consisting of similar plastic material incorporated with springy granulated material.

9. A playing-ball having a cover comprising an inner and outer casing of celluloid and an 55 intervening layer consisting of granulated cork incorporated with pyroxylin and uniting said casing, and a filling held under compression by said cover.

10. A playing-ball having a shell comprising an inner and outer celluloid casing, an intervening layer consisting of granulated cork incorporated with pyroxylin, and a sphere of soft rubber inclosed by said shell.

11. A playing-ball comprising a plurality of 60 spheres of similar plastic material united by a layer of similar plastic material incorporated with cork, the cork being held under compression.

12. A playing-ball comprising a core and a 65 plurality of spheres thereon of plastic material united by a layer of similar plastic material incorporated with cork, the cork being held under compression.

13. A playing-ball comprising a core and a 70 plurality of spheres thereon of plastic material separated by a layer of similar plastic material incorporated with compressed cork; said cork being held under compression.

14. A playing-ball comprising a center 75 piece, a layer of soft rubber thereon, a shell of celluloid upon said soft rubber, a layer of cork and pyroxylin upon said celluloid, and a cover of celluloid; said cork being held under compression.

15. A playing-ball comprising layers of celluloid, an intervening layer of granulated cork incorporated with pyroxylin, said celluloid layers being united to said intervening 80 layer, and a springy core filling the inner of 85 said celluloid layers.

16. A playing-ball comprising spheres of celluloid between which is confined a layer of granulated cork incorporated with pyroxylin, said celluloid layers being united to said confined 90 layer.

17. A playing-ball comprising a plurality of spheres of celluloid and a composition of granulated cork incorporated with pyroxylin uniting 95 said spheres.

Signed at Nos. 9 to 15 Murray street, in the city and State of New York.
